PILE DRIVER

Herman R. Smith, Douglaston, N. Y., assignor to
 Raymond Concrete Pile Company, New York,
 N. Y., a corporation of New Jersey

Application November 15, 1933, Serial No. 698,097

3 Claims. (Cl. 61—74)

This invention pertains to pile drivers, and the object of the invention is to disclose a pile driver adapted for rapidly and economically driving batter piles, even when the same job calls for piles at widely different angles, or, as sometimes happens, at reversed angles.

In general, the invention comprises pile driver leads supported on the boom of a crane, in combination with means, preferably operable by power, for adjusting the position of the leads and for holding them firmly in any operative position.

The invention is illustrated in connection with the Sea Wall job disclosed in Upson application Ser. No. 686,910, filed Aug. 26, 1933, in which sheet piles were driven at a slight batter in one direction, and bracing piles were driven at spaced intervals with a pronounced batter in the opposite direction. On that job two separate machines might have been used, one with its leads fixed at an angle in one direction for the sheet piles, and the other with its leads fixed in the other direction for the bracing piles. But the use of two machines would have added greatly to the cost of operation.

In the use of machines with fixed batter it is a very difficult matter to place the piles in the leads, especially when the piles are of concrete and very heavy. In the present machine that difficulty is avoided. The leads are so readily adjustable that they may be moved to a vertical position to receive the pile and support it until the pile head is entered into the follower under the hammer, and the pile point is placed in a suitable guide, after which the leads (and pile) are quickly set at the proper angle and position for driving.

During the driving operation it is of great importance that the lower ends of the leads be braced against sidewise motion. This is accomplished in the present invention by a slidable frame interconnecting the leads and the base of the crane, as will appear.

Further and other objects and advantages will be apparent from the specification and claims, and from the accompanying drawings which illustrate what is now considered the preferred embodiment of the invention.

Fig. 1 is a side view of the apparatus showing the leads in a full-line position for driving the sheet piles, and in a broken-line position for driving the bracing piles.

Fig. 2 is an enlarged detail view of apparatus for adjusting the lower ends of the leads.

Fig. 3 is a plan view on line 3—3 of Fig. 2.

Fig. 4 is a view on line 4—4 of Fig. 2.

Fig. 5 is a view of a modified form of the invention.

Fig. 6 is a view on line 6—6 of Fig. 5.

The pile driver leads 10, with their structural steel supporting structure 12, are pivotally mounted at 14 on boom 16. The lower ends of the boom guy wires 17 are anchored at 18 on castings 20 which form part of the base structure 22 of the machine and the boom itself is pivoted on the same line. Base 22 is usually mounted for rotation on a turn-table 24, and is illustrated in the present instance as extending rearwardly to support the hoisting drums with their power plant, and forwardly to support the devices of the present invention which are operable for positioning and bracing the lower ends of the leads.

Boom 16 is movable through a wide angle under control of cable 26. When the cable is drawn in the boom is swung rearwardly, and when the cable is slackened off, the boom, actuated by the weight of the lead structure hammer, etc., swings forwardly and downwardly. In Fig. 1 the full-line drawing shows the leads in position for driving a sheet pile 28, while the broken line drawing shows them in position for driving a bracing pile 30. Line 32 is the center line of boom 16 while pile 30 is being driven.

For adjusting the position of the lower ends of the leads, and for supporting them rigidly in adjusted position the mechanism now to be described is provided.

Supported at the rear of the lead structure by frame work 34 and angle guides 36, is a cross-head 38 usually built of structural steel and adapted to slide snugly in guide 36, parallel to the leads. Pivotally connected to the lower end of crosshead 38 at 40, are the forward ends of horizontal beams 42, 44, the rear ends of which are joined by cross channels 46, 48 and 50, 52 forming a box girder in which is a threaded nut 54 mounted on a vertical trunnion 56. A horizontal screw 58 passes through the nut parallel to beams 42, 44 and midway between them, the rear end of the screw being supported for rotation in a journal box 60. Fast on the screw is a gear 62 in mesh with pinion 64 on the extended shaft 66 of a reversible steam engine 68 mounted on the frame of the machine. The screw is restrained from longitudinal movement by collars 70, 72 at the ends of journal 60, therefore, when the screw is rotated in either direction by the engine, beams 42, 44 are moved forwardly or

rearwardly to properly position the lower ends of the leads.

Beams 42, 44 are guided for accurate longitudinal movement and restrained against side-wise or vertical movements by side rollers 14, 16, 18, 80, by overhead rollers 82, 84, 86, 88, and by underneath rollers 90, 92, 94 and a roller (not shown) opposite 94, all suitably supported, as will be apparent from the drawings, in a structural steel framework having side channels 96, 98. This guiding structure is rigidly mounted on base structure 22.

From the above it will be readily understood that manipulation of boom 16 and screw 58 will 15 quickly place the leads in position to sink batter piles at any angle within the range of angular adjustment provided in the machine, for instance, the two positions shown in Fig. 1. Furthermore, the leads are continuously and automatically held fixed in any position until 20 moved at the will of the operator.

Figs. 5 and 6 show a slightly different embodiment of the invention in which crosshead 38 is omitted, beams 42, 44 being pivotally connected 25 at 40 to brackets 100 integral with the lead structure, and in which the fixed-length boom 16 is replaced by a telescopic boom comprising an inner lower section 102 and an outer upper section 104, both formed of structural steel, as will 30 be sufficiently apparent from the drawings.

The screw mechanism for adjusting the length of the boom is similar to that already described except that, for convenience, two screws, 106, 108 are used, passing through nuts 110, 112 on the 35 sides of upper section 104, the lower ends of the screws rotating in bearings 114, 116 and 118, 120 on lower boom section 102. The thrust of the screw is taken by bearings 118, 120 through suitable collars. Screws 106, 108 are actuated 40 simultaneously to lengthen or shorten the boom, by another reversible steam engine 122 through its extended shaft 124, worm 126, worm gear 128, shaft 130, bevel gears 132, 134, and pinions 136, 138 fast on the lower ends of the screws. By 45 using engines 122 and 68 the leads may be moved rapidly to any desired angular position, and at any position the leads are automatically held rigidly in that position.

In describing the invention it has not been 50 considered necessary to discuss the hammer, hoisting apparatus and other necessary parts of

the machine, indicated in Fig. 1 of the drawings, all of which parts are well understood by those skilled in the art.

It is to be understood that the invention is not limited to the specific embodiment herein illustrated and described, but may be used in other ways without departure from its spirit as defined by the following claims.

What I claim is:

1. In a pile driver having a base, in combination, a lead structure, a boom supporting said structure, a support adapted for rectilinear movement carried by said base, means comprising a cross-head slidable in said lead structure for pivotally connecting said support and the lead structure, and means for operating said boom to move said lead structure about its pivotal connection on said support, said adjustable support and the sliding connection between the lead structure and the cross-head being operable 20 to place the lead structure in position to drive batter piles at various angles.

2. In a pile driver having a base, in combination, a lead structure, a boom supporting said structure, a support adapted for rectilinear 25 movement carried by said base, means comprising a cross-head slidable in said lead structure for pivotally connecting said support and the lead structure, means for moving said support upon its base to place the lower end of said 30 lead structure in various positions, and means for operating said boom to swing said lead structure about its pivotal connection on said support, both of said last mentioned means operable to place the lead structure in position to 35 drive batter piles at various angles and the sliding connection between the lead structure and the support allowing for such swinging movement of the lead structure.

3. In a pile driver having a base, in combination, a structure supporting a pair of leads, means carried by said base and having a horizontal pivot for supporting said structure, a support adapted for rectilinear movement carried by said base, means comprising a cross-head 45 slidable in said lead structure for interconnecting said support and said structure, and means for moving said support for adjusting said structure about said horizontal pivot to position said leads for driving batter piles at various angles.

HERMAN R. SMITH.
